COMPOSITE SHIP CONSTRUCTION

Clement Paul Cueni, Arlington, N. J., assignor to
 Porete Manufacturing Company, Arlington,
 N. J., a corporation of New Jersey

Application January 21, 1942, Serial No. 427,648

14 Claims. (Cl. 114—65)

The present invention relates to reinforced concrete ships, barges and floating docks.

The idea of using reinforced concrete instead of steel in the construction of ships and barges is not new. About thirty years ago the first concrete ship was built and during the first World War a great number of seagoing concrete ships were constructed in various countries. Though these ships proved to have a number of advantages against steel ships they did not fulfill the expectations of the designers.

Concrete ships built according to the heretofore used methods were too heavy and therefore could not carry as much heavy cargo as a steel ship of the same size. The bending and placing of the reinforcing bars and keeping them in the right place during pouring and setting of the concrete was too complicated and required too much time. Therefore the introduction of the reinforcing bars in place was quite expensive and the time of construction was too long. Concrete is a brittle material and cannot as well withstand local blows and scratches resulting from rough handling or accidents as steel can. Therefore, puncturing of the shell with resulting leakages occurred too frequently and made expensive lay-offs for repairs necessary.

It is among the objects of the present invention to eliminate the above mentioned disadvantages of concrete ships, concrete barges or concrete docks.

It is also among the objects of the present invention to provide a new design in which the keelsons, frames and beams, composed of structural steel shapes forming together a rigid steel skeleton, are connected by shear reinforcements to the concrete hull, or to the concrete deck slab or both, in such a manner that the concrete slab with the members of the steel skeleton form composite sections.

It is another object of the present invention to provide means for facilitating the placing of the forms, the placing of the reinforcing bars and holding them in place during pouring and setting of the concrete.

It is another object of the present invention to provide a frame design wherein square panels are formed by the ribs, making possible the design of a hull shell, which takes advantage of a two way reinforcement.

It is still another object of the present invention to provide a flexible concrete hull not subject to shrinkage cracks, and having a much higher resistance against local blows, by prestressing the reinforcing bars.

It is a further object of the present invention to provide a rigid skeleton serving as ribs for the concrete shell and connected thereto by an effective shear reinforcement, the skeleton being designed to withstand the forces produced by prestressing the steel wires used for reinforcement of the concrete shell.

It is a still further object of the present invention to provide a rigid skeleton upon which precast concrete slabs are fastened in such a way that the slabs, forming the hull shell, or the deck, form a composite section with the members of the skeleton to which they are fastened.

It is not new to use a rigid steel skeleton in the construction of concrete ships. It was realized long ago that the placing of the reinforcing bars without the help of such a skeleton was too complicated and took too much time and required too accurate a bending of the bars and therefore was expensive. But the members of the skeleton were not designed as composite sections together with the concrete hull, and so a disadvantage was eliminated at a high cost. More steel was required, and the dead load increased.

According to the present invention the concrete ribs of a reinforced concrete ship are simply replaced by plain steel ribs forming a composite section together with the concrete hull. Such a section has by necessity the same section modulus as the reinforced concrete T section and the same moment of inertia or a greater one. Compared with a rib of a steel ship of equal section modulus it has a much higher moment of inertia and therefore is stiffer.

The advantages of a plain steel rib forming composite section with the concrete hull are substantial. All the concrete in the ribs is eliminated and the dead weight reduced. The rib concrete in a ship built according to the heretofore used method amounts to from 30% to 50% of the total concrete used. The reduction in dead weight is therefore considerable.

In the heretofore used method the formwork was complicated and had to be supported by falsework. In a ship built according to the present invention the formwork is much simpler, as no forms for ribs are required, and at least the inside forms are supported by the rigid skeleton. The forms can be placed much faster.

In the heretofore used method much time was required to bend and place the reinforcing bars. With the new method according to the present invention less reinforcing bars are required, since there are no rib bars, and the bending and the placing of the remaining bars is much easier.

The bars do not have to be bent accurately to the shape of the hull because they can be fastened to the shear reinforcement welded to the steel skeleton, which will hold them in the right position during the pouring and setting of the concrete.

To use two-way reinforcement in square or almost square concrete slab panels is not new but in the construction of concrete ships advantage of the two-way reinforcement could not be taken because cross ribs would further complicate the formwork and the advantage gained in the shell itself is lost by the addition of heavy cross ribs. With composite design the cross ribs, being plain steel, add very little to the dead weight and make possible a reduction in the reinforcement or thickness of the shell.

Probably the greatest disadvantage of concrete ships or barges is the brittleness of the concrete. In ships built according to the heretofore used method punctured shells occurred too often and made frequent lay-offs necessary for repairs. Sometimes the apparent damage to the shell from slight blows was small, but upon careful examination the concrete was found to be cracked, and leakage resulted, making repair necessary. In ships built according to the present invention this disadvantage and also the forming of shrinkage cracks is eliminated, and at the same time the amount of reinforcing in the shell is reduced by 40% to 60%, thus reducing further the dead weight.

By using high strength steel wires with small diameter and prestressing them to such a degree that no design stress, taking into consideration shrinkage and plastic flow of concrete, will produce any tensile stresses in the concrete, a new reinforced concrete is formed which has almost the same elastic properties as steel or wood. Instead of using high tensile steel wires intermediate grade reinforcing bars prestretched beyond the yield point before being placed, can also be used. Such a concrete slab can be bent considerably by an external force without getting tension cracks and after the external force is removed the slab will move back to its original position. But even if the external force is strong enough to produce bending in such a degree that tension cracks appear, it does not necessarily mean permanent damage to the concrete slab. If the stresses in the steel wires are still below the ultimate yield point when the external force is removed, the slab will move back to almost its original position and tension cracks in the concrete will be closed hermetically by the internal forces introduced into the slab by highly prestressing the wires.

The prestressing of the reinforcing bars in one direction is enough since by releasing the prestressing force after the concrete has set, some prestresses are introduced in the reinforcing bars running in the direction perpendicular to the prestressed bars. Some of the advantages of prestressed concrete can be achieved by prestressing only part of the reinforcing bars running in one direction, the other bars being normal reinforcing without any prestressing. Such a prestressing can be so designed that it is effective enough to make impossible any formation of shrinkage cracks. It would provide the concrete slab with more flexibility than possessed by a conventional concrete slab.

By prestressing the reinforcing bars, for instance the longitudinal bars of the hull, lateral forces are produced, due to the curved shape of

the hull. Some frame has to be provided to take care of these lateral stresses. The steel skeleton, members of which are designed to form the ribs for the reinforced concrete hull, can well serve for this purpose, so that no special frame is required. After the external force, producing the prestressing, is released the prestressed reinforcement will produce stresses in some members of the rigid skeleton which, being of opposite sign than the stresses produced by the normal forces acting upon the structure, may be used to reduce the required section modulus of such members.

The use of precast slabs in the construction of concrete ships has several advantages. Precast slabs can be made at less cost and of higher ultimate strength concrete than a hull poured in place. The prestressing of precast slabs also is easier than the prestressing of a hull poured in place. The precast slabs can be poured in advance during the fabricating and assembly of the skeleton, and the fastening of them to the steel frames will take less time than the pouring of the entire hull. Therefore, the construction of a ship with precast slabs will require the ship ways for a shorter time than a ship poured in place. If the hull is damaged repair is simpler with precast units. The damaged slabs are simply replaced by new ones and no sensitive joints of old and new concrete are the result of such repair.

A prerequisite for the speedy erection of the precast slabs is a rigid skeleton to which the slabs can easily be fastened. To use a rigid steel frame for that purpose is not new, but it is new to fasten the precast reinforced concrete slabs in such a way that slabs and steel ribs form one statical unit and are designed as such.

The precast slabs are provided with a light steel frame on all four sides, facilitating the handling and erection of the slabs and which frame is arc welded to the steel ribs, thus making a tight joint.

The objects and the nature of the present invention will be more fully explained in the accompanying drawings constituting a part hereof and in which like reference characters indicate like parts. Since the drawings are merely an illustration of the claims they shall in no way be construed as a restriction thereon.

Fig. 5 is a cross section of a side frame;

Fig. 6^a is a plan of a frame panel;

Fig. 6^b is a cross section through such a panel;

Fig. 7 is a plan view of the bottom of a ship;

Fig. 8^a is a cross section of a frame showing the connection of precast slabs;

Fig. 8^b is a plan view of such a joint, and

Fig. 9 is a cross section of a frame showing a joint of a precast slab with concrete poured in place.

In Fig. 1 there is shown the rigid steel skeleton composed of keelson 1, floor beam 2, side frame 3, deck beam 4, cross frames 5, a concrete shell 6 and deck slab 7. The steel skeleton is one unit, all members 1 to 5 being riveted or welded together. The concrete shell 6 and deck slab 7 are connected to the members 1 to 5 of the skeleton by a steel shear spiral 8 or other effective shear

reinforcement in such a way that the members 1 to 5 of the steel skeleton form composite sections with the reinforced concrete shell 6 or the deck slab 7, respectively. The shear reinforcement must be designed to transmit the shear between the steel rib and the concrete slab, in a similar way as the rivets connecting the steel rib with the steel shell in a plain steel ship.

The main frames in such a ship may be cross frames, as shown in Fig. 1 under 2, 3 and 4 or they may be longitudinal frames running parallel to the keelson, like the cross frames 5, in Fig. 1. The frames 2, 3 and 4 are then reduced to lighter cross frames.

The steel skeleton may be composed of all welded sections, riveted sections or rolled sections. All-welded sections require less steel than riveted or rolled sections and are more economical, except maybe for light members, where rolled sections probably are as economical as welded ones, for instance for the cross frames 5.

The concrete shell or deck slab may consist of plain reinforced concrete, the main reinforcement running in one or two directions, perpendicular or diagonal to the frames, or of a prestressed reinforced concrete, where part or all of the main reinforcement is prestressed.

In the longitudinal section Fig. 2, 1 shows the keelson, 2 the cross section through the floor beams, 5 the cross frames, 6 the reinforced concrete shell of the bottom of the ship and 8 the shear spiral.

The spacing of the frames is a matter of design and depends on the type and size of the ship, on the thickness and reinforcement of the concrete slab, and the properties of the concrete and reinforcing steel.

In the cross section Fig. 3, 1 is the keelson, composed of three plates welded together into an I shape, forming a composite section together with the concrete shell 6, 2 is the floor beam, framed into the keelson. The top flange 9 of I-beam shape is much heavier than the bottom flange 10, which is increased by the area of the concrete slab 6 and its longitudinal reinforcement 11, 12, 13, 15 and 16. The spiral shear reinforcement 8, welded to the flange of the keelson 1, serves as a base to which reinforcing bar 13 is welded, which serves as a chair to keep the exterior cross reinforcement 14 of the slab in its right place during pouring and setting of the concrete. In a similar way the bars 15 and 16, welded to the spiral serve as a chair for the interior cross reinforcement 17 of the concrete slab. 8a is a side view of the spiral shear reinforcement, welded to the floor beam 2, and 18 is an additional interior cross reinforcement for the concrete haunch.

In the cross section Fig. 4, 2 is a floor beam composed of three plates welded together into an I-beam shape, forming a composite section together with the concrete shell 6.

The spiral shear reinforcement 8, welded to the floor beam 2 supports bars 19 and 20 which serve as chairs for the longitudinal interior reinforcing bars 12, and bar 21, also welded to the spiral 8, serves as a chair for the exterior reinforcing bars 11 of the concrete shell.

5 is a cross frame welded to the floor beam 2. 8a is a side view of the shear spiral welded to the cross frame 5. 14 is the exterior cross reinforcement and 17 the interior cross reinforcement.

In the cross section Fig. 5, 3 is the side frame composed of three plates welded together into an I-beam shape, forming a composite section

together with the concrete shell 6. The shear spiral, the chair bars and the slab reinforcement is the same as shown in Fig. 4. The bar 22 is the concrete haunch reinforcement also shown in different shape in Figs. 3 and 4.

Bent in this shape and placed alternately, one in this direction and the next in the other direction, it provides a concrete haunch reinforcement and also additional negative reinforcement for the concrete shell over the frames.

The inside formwork 23 supported by the cross pieces 24 can easily be attached by the wedges 25 and inserts 26 to the steel frames. It is obvious that after the steel skeleton is erected with the shear spirals welded to it, the placing of the reinforcing bars is facilitated and expedited considerably as compared with the heretofore used method of building concrete ships. The placing of the interior formwork is simplified; no forms are needed for ribs and no scaffolding is necessary, since the forms are supported by the steel skeleton as shown in Fig. 5.

In Figs. 6a and 6b, 2 shows a floor beam, 5 a cross frame, 8 a shear spiral and 6 the reinforced concrete shell. 11 and 14 show the exterior slab reinforcing, running in both directions, 12 and 17 is the interior slab reinforcement. 19, 20 and 21 are the reinforcing bars welded to the spirals and serving as chairs for the slab reinforcement. 22 is the haunch reinforcement placed across the frames. Each panel is square or almost square, which will allow advantage to be taken of a two-way reinforcement. For the same thickness of slab and the same reinforcement a greater spacing of the frames will be possible. The slab is also made stronger by heavy edges formed by the haunches on top of the frames, indicated by the dotted lines 27 and shown at 28 in cross section, Fig. 6b. If no advantage is taken of two-way reinforcement the cross frames 5 can be reduced considerably in number and size. However, a heavier slab is then required, and the floor beams, side frames and deck beams must be spaced closer together.

Fig. 7, being the plan of the bottom of the steel skeleton, shows the keelson 1, the floor beams 2, the side frames 3, the cross frames 5, and the concrete shell 6.

29 is a bulkhead consisting of a concrete slab and steel frames. It may be advisable to omit the steel floor beam, side frame and deck beam where bulkheads are required, except where lateral forces occur. The arrows 30 show these lateral forces produced by prestressing the longitudinal reinforcing bars. These forces can be taken by the steel skeleton, without any additional temporary frames.

In Fig. 8a, 31 represents the cross section of one of the frames, floor beams or the keelson. In Figs. 8a and 8b, 8 is a shear reinforcement in the form of a spiral, 32 a precast reinforced concrete slab forming the shell and 33 the concrete shell cast in place after the slabs 32 are erected and welded to the frame. In pouring the precast slabs 32, angles 34 or 35 are attached to the slab by shear bars 36 which are shaped into a waved form and welded to the angles 34 or 35. One of the two welds 37 or 38 by which angles 34 or 35 are welded to the frame should be continuous to make the joint watertight, the other one may be intermittent.

The reinforcing bars 39 and 40 sticking out of the precast slabs 32 are bent over the chair bars 41 and 42 and wired or welded thereto. The reinforcing bars of the precast slabs also can be

welded to the corresponding reinforcing bar of the adjacent precast slab. The reinforcing bars 43 and 44 running in opposite directions also stick out on both ends and are connected in a similar way. Ordinary high strength reinforced concrete may be used for the precast slabs 32, and the shell 33, poured in place. Preferably some or all of the bars running longitudinally of the ship are prestressed. Prestressing in both directions is not required as the prestressing in one direction will automatically bring about a prestressing in the other direction, according to Poisson's law.

The slabs 32 may have indentures 45 on all four sides to increase their bond to the concrete 33 poured in place.

It may be of advantage to use precast slabs only for part of the shell, for instance for the side walls and there only where the slabs will be plane or almost plane. The rest of the hull then would be poured in place. A cross section through a frame where poured-in-place and precast concrete meet is shown in Fig. 9. 31 is the cross section of a steel frame, 32 the precast slab, and 46 the concrete poured in place forming frame haunch and hull shell. The reinforcing bars and the shear reinforcements are about the same as shown in Figs. 8^a and 8^b, except that the bar 47 is at a greater distance from bar 39 than bar 39 in Fig. 8 is from bar 40. This is due to the increased thickness required for the poured-in-place concrete which also may not be prestressed. The same is true for bars 43 and 48.

The prestressing of the reinforcing bars of the precast slabs is so designed that the initial stresses on such slabs, after erection in the vessel, due to conditions encountered in service, will tend to neutralize such prestresses before placing positive stress on such slabs. Thereby the strength of the structure is increased and the weight of the vessel may be correspondingly decreased. The principles of my copending application Ser. No. 402,618 filed July 16, 1941 may be applied for this purpose.

Although I have described the invention by the use of certain descriptive terms, they are not to be given a restricted meaning but should be considered in the broad sense. For instance, in place of steel, alloys thereof or other metals may be substituted. Bars or rods are intended to include various sizes and forms used for reinforcing purposes. Union of metal parts may be by welding, riveting, wiring, clamping, or other common expedients. Shear reinforcement is not necessarily spiral, but other forms designed to give the effect may be used, such other forms being well-known. The slabs and poured-in-place concrete are intended to be applicable to bottom, sides, floors, decks, bulkheads, partitions, and the like. Vessel designates not only propelled ships, but also scows, barges, floats, docks, and even other than marine structures in which there may be a rigid skeleton and concrete can be applied to give the present results.

The present invention has introduced new principles into composite steel-concrete construction and the invention is, therefore, to be broadly construed and not to be limited except by the claims appended hereto.

What is claimed is:

1. A marine vessel comprising a substantially rigid steel skeleton, relatively stiff, substantially continuous shear reinforcement integrally secured to said skeleton and extending laterally outward therefrom, a reinforced concrete shell

made up of flat slab members secured to said skeleton, said shear reinforcements projecting upwardly into the space between adjacent concrete slabs, reinforcing members extending from the ends of said slabs and locked to said shear reinforcements, concrete poured and set in said space and in which said reinforcing members and shear reinforcements are embedded, the junction being such that said skeleton and members are locked together through said reinforcements to form composite sections by union through said shear reinforcement by poured-in-place concrete.

2. A marine vessel comprising a substantially rigid steel skeleton having panels of substantial length and width, reinforced concrete outer members secured to said skeleton, said members being precast, having reinforcing at least part of which is prestressed and fitting into said panels, the junction being such that said skeleton and members form composite sections and being linked by substantially continuous, relatively stiff shear reinforcement integral with said skeleton, said linkage being through the fastening of said reinforcements with the metal of said reinforced concrete.

3. A marine vessel comprising a substantially rigid steel skeleton having panels of substantial length and width, shear reinforcement integrally secured to said skeleton, reinforced concrete outer members secured to said skeleton, said members being precast and fitting into said panels, the junction being such that said skeleton and members form composite sections, and poured-in-place concrete uniting said elements through said reinforcement to form a unitary structure.

4. A marine vessel comprising a substantially rigid steel skeleton, shear reinforcement integrally secured to said skeleton, reinforcing bars for concrete secured to said shear reinforcement, said bars being prestressed longitudinally of said vessel, said skeleton taking said prestresses, and concrete poured in place around said bars and shear reinforcements to form at least part of said vessel.

5. A marine vessel comprising a substantially rigid steel skeleton having panels of substantial length and width, shear reinforcement integrally secured to said skeleton, reinforced concrete outer members secured to said skeleton, said members being precast and fitting into said panels, the junction being such that said skeleton and members form composite sections, and poured-in-place concrete uniting said elements through said reinforcement to form a unitary structure, at least one end face of said members having an indenture to lock into said poured-in-place concrete.

6. A marine vessel comprising a substantially rigid steel skeleton, shear reinforcement integrally secured to said skeleton, reinforced concrete outer members secured to said skeleton, the reinforcing of said members extending beyond the ends of said members, the junction being such that said skeleton and members form composite sections by union through said shear reinforcement, chair bars fastened to said shear reinforcement longitudinally thereof and adapted to hold in place the reinforcing of said members.

7. A marine vessel comprising a substantially rigid steel skeleton, shear reinforcement integrally secured to said skeleton, reinforced concrete outer members secured to said skeleton, the junction being such that said skeleton and

members form composite sections by union through said shear reinforcement, chair bars fastened to said shear reinforcement longitudinally thereof and adapted to hold in place the reinforcing of said members, the latter being made of poured-in-place concrete.

8. A marine vessel comprising a substantially rigid steel skeleton having panels of substantial length and width, shear reinforcement integrally secured to said skeleton, reinforced concrete outer members secured to said skeleton, said members being precast and fitting into said panels, the junction being such that said skeleton and members form composite sections, the reinforcing of said members extending beyond at least one end thereof and secured to the adjacent shear reinforcement.

9. A marine vessel comprising a substantially rigid steel skeleton having panels of substantial length and width, shear reinforcement integrally secured to said skeleton, reinforced concrete outer members secured to said skeleton, said members being precast and fitting into said panels, the junction being such that said skeleton and members form composite sections, the reinforcing of said members extending beyond at least one end thereof and secured to the adjacent shear reinforcement, and poured-in-place concrete uniting the same.

10. A marine vessel comprising a substantially rigid steel skeleton having panels of substantial length and width, shear reinforcement integrally secured to said skeleton, reinforced concrete outer members secured to said skeleton, said members being precast and fitting into said panels, the junction being such that said skeleton and members form composite sections, said members having steel edge pieces permanently secured to said skeleton.

11. A marine vessel comprising a substantially rigid steel skeleton having panels of substantial length and width, shear reinforcement integrally secured to said skeleton, reinforced concrete outer members secured to said skeleton, said members being precast and fitting into said panels, the junction being such that said skeleton and members form composite sections, said members having steel edge pieces permanently secured to said skeleton by being welded to structural shapes thereof.

12. A marine vessel comprising a substantially rigid steel skeleton having panels of substantial length and width, reinforced concrete outer members secured to said skeleton, said members being precast and fitting into said panels, the junction being such that said skeleton and members form composite sections and being linked by substantially continuous, relatively stiff shear reinforcement integral with said skeleton, said members having steel edge pieces permanently secured to said skeleton by being welded to structural shapes thereof, at least one of said pieces being continuous and being welded along its entire length to provide a water-tight joint, and poured-in-place concrete between adjacent members, said concrete having embedded therein said shear reinforcements and steel pieces.
13. A marine vessel comprising a substantially rigid steel skeleton having panels of substantial length and width, reinforced concrete outer members secured to said skeleton, said members being precast and fitting into said panels, the junction being such that said skeleton and members form composite sections and being linked by substantially continuous, relatively stiff shear reinforcement integral with said skeleton, said members having steel edge pieces permanently secured to said skeleton, shear bars secured to said pieces and embedded in said members, and poured-in-place concrete between adjacent members, said concrete having embedded therein said shear reinforcements and steel pieces.
14. A marine vessel comprising a substantially rigid steel skeleton having panels of substantial length and width, reinforced concrete outer members secured to said skeleton, said members being precast and fitting into said panels, the junction being such that said skeleton and members form composite sections and being linked by substantially continuous, relatively stiff shear reinforcement integral with said skeleton, said members having steel edge pieces permanently secured to said skeleton, said pieces being angular in cross-section and located at corners of said members, and poured-in-place concrete between adjacent members, said concrete having embedded therein said shear reinforcements and steel pieces.

CLEMENT P. CUENI.
